UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,366,376.

Specification of Letters Patent. Patented Jan. 25, 1921.

Application filed July 12, 1917. Serial No. 180,046.

To all whom it may concern:

Be it known that I, FRANZ A. FULLER, a citizen of the United States, residing in the city of Newark, in the county of Essex and State of New Jersey, have invented certain new and useful Improvements in Bag-Fasteners, of which the following is a full, clear, and exact description, such as will enable others skilled in the art to which it pertains to make, construct, and use the same, reference being had to the accompanying drawings, and to characters of reference thereon, forming a part of this specification.

My invention relates to bag fasteners, and more particularly to a type thereof applicable to bag frames having pivotally connected jaws or frame members embodying therein interlocking members adapted to lock said frame members when closed. The jaws of the ordinary forms of hand bags, pocket books, satchels or the like, are all provided with interlocking members, such as lift latches, balls or heads which spring or snap past each other to hold the jaws together. If the hand bags or the like be unusually full, or if either of the projecting members constituting the fastener, or the jaws themselves, becomes bent or loosened, it often happens that the jaws are accidentally opened and the contents of the bag lost or abstracted without the knowledge of the owner.

My invention comprises a new and improved locking means for hand bags and the like, and by which I seek to overcome the objections found in those heretofore employed. In order to eliminate the above-mentioned evils and overcome these objections, I have devised a new lock, which has all the advantages of manipulation of a center lock, and to combine with it the feature of locking the bag frame at two points, said lock being designed to coact with the ordinary lock or fastener, for preventing accidental loosening or unfastening of the same.

My invention consists primarily of a bag fastener embodying therein a frame, consisting of hinged frame members, interlocking catch members carried by said frame members for normally holding said frame members closed, of an auxiliary fastening member rotatively secured to one of said interlocking catch members and having locking engagement with the other of said catch members, or the frame members to which

said last-mentioned fastening member is secured, said auxiliary fastening member being designed to coact with one of the interlocking fastening members or one of the frame members for preventing accidental loosening or unfastening of the same.

With the various objects of my present invention in view, the same consists in the novel bag frame fastener hereinafter set forth; and, furthermore, this invention consists in the various arrangements and the parts thereof, all of which will be fully described in the accompanying specification, and then finally embodied in the clauses of the claim thereof, which are appended to and form an essential part of this specification.

In the drawings,

Figure 1 represents a front view of a bag frame showing my improved fastener secured thereto.

Fig. 2 represents an end view of the frame, the hinged or pivoted members being represented in open relation to each other.

Fig. 3 represents an enlarged front view of the fastener, the pull piece not being shown.

Fig. 4 represents an enlarged vertical section of the frame and fastener, taken on line a—a of Fig. 1.

Figs. 5, 6 and 7 represent respectively, front, end, and rear views of the spring used in connection with the fastener.

Figs. 8 and 9 represent front views of the interlocking catch members.

Fig. 10 represents a front view of the latch stud; and

Fig. 11 represents a vertical section of the same, taken on line x—x of Fig. 10, and looking in the direction indicated by the arrow.

Similar characters of reference are shown in all of the above described views, to indicate corresponding parts.

A bag frame fastener or holding catch made in accordance with my invention, may be applied to any ordinary or desired form of frame; that shown in the drawings, consists of the two frame members 1 and 2 of substantially the same shape. To the middle portions of these members 1 and 2, I secure the fasteners or catches 3 and 4, as in this particular instance shown, by means of the fastening nibs 5, formed integral with the base of the fastener, which nibs pass through suitable apertures in the frame,

and are clenched over in any suitable or convenient manner on the under side thereof. Each fastener is made up of the rigid base 6, and the upwardly extending knob 5 or ball 7, the base being formed preferably of flat stock, although round wire stock, if desired, may be employed. The base 6 is provided on its under side, which comes in contact with the frame member, when the same is secured thereto, with the integral nibs 5, which as heretofore stated, are inserted through the apertures common in bag frames and riveted down in the usual manner, to secure the fastener rigidly to the bag frame, and one of the bases is further provided with a centrally cut-away portion for the reception of the spring illustrated in Figs. 5, 6 and 7 of the drawings.

Each base has formed centrally therein, 20 an aperture 7' and 8 respectively, the object of which will be presently described. With this construction, the two hinged members always come together with a very pronounced snap, due to the hinge members 25 1 and 2.

In my improved device, I provide a second locking device for holding the jaws together, which locking device is rotatively and preferably secured to the base of the 30 catch or fastener 3, and is operated independently of the catch members above described.

In the specific form illustrated, I employ a latch stud 9 mounted to turn in the suitably alined aperture 7' formed in the base 6 of the catch or fastener 3, which is preferably made from cylindrical metal rod, the outer end being provided with an enlarged head 10, the inner portion of which bears 40 against the outside of the U or channeled-shaped spring 19 which is positioned in the cut-away portion 11 of the base 6, and the cylindrical portion of which bears upon the top of the frame member 1, which serves to 45 limit the inward movement of the latch, and forms a bearing for the same on the frame member 1, when it is being assembled. A pull piece 12, of any convenient form, is pivotally secured in an aperture formed in 50 the enlarged head 10, to facilitate manipulation, and a beveled latch head 13, formed integrally on the opposite or inner end of the stud 9, is designed to pass through the suitably alined aperture 8, see Fig. 9, 55 formed in the base 6 of the catch or fastener 4, and to have holding engagement therewith, or with a suitable nosing or projection 14 formed on the frame member 2, see Fig. 4, to firmly secure the bag frame sections or 60 members in locked position, for additionally holding the frame members 1 and 2 together.

The latch stud 9 is controlled and held in position by the reduced portion 15, which is rotatively secured in the aperture 7' of 65 the base 6 of the catch or fastener 3. An

annular flange 16 is formed on the latch stud 9, said annular flange being provided with a pair of projections 17, preferably integral and formed by forcing the metal of the flange outwardly, said projections 17 being 70 designed to engage with suitable recesses 18 formed in one side of the spring 19, which is located on the inside of the base 6 and interposed between said base and the annular flange 16. 75

The spring as indicated in Figs. 5, 6 and 7 of the drawings, is made from a single piece of suitable material, bent centrally so as to fit into the cut-away portion 11 of the base 6, by means of which the spring is positioned 80 and secured to the base when the base is secured to the frame member.

As indicated in the drawings, both sides of the spring 19 are provided with suitable apertures 20, through which the reduced portion 15 of the stud 9 passes. The rear side of the spring is a trifle higher than the front side, and the aperture 20 in the rear side has communicating therewith diametrically oppositely-arranged recesses 18, 90 designed to receive the projections 17, which are integrally formed on the annular flange 16 formed on the latch stud 9, so that when the spring is secured to the base, and the base is mounted on the frame member, the 95 short side of the spring will lie between the front side of the base 6 and the inner portion of the enlarged head 10, and the rear side of the spring will lie between the rear of the base 6 and the annular flange 16, as 100 clearly indicated in Fig. 4 of the drawings.

The rear side of the spring is preferably located a very slight distance away from the rear of the base 6, so that when the latch stud is rotated, the rear side of the spring 105 will exert a slight spring pressure against the annular flange 16, at the same time preventing the latch stud from swinging when the bag is in use. When the latch stud is in either the locked or unlocked position, the 110 projections 17 will engage with the recesses 18 of the spring, as clearly indicated in Fig. 4 of the drawings.

In assembling the device, the reduced portion 15 of the latch stud 9 is inserted in the apertures 20 of the spring 19, so that the inner face of the enlarged head 10 bears against the outside of the front side of the spring, and the annular flange 16 bears against the rear side of the other side of the 115 spring, with the projections 17 registering with the recesses 18. The latch stud is then rotatably secured to the base by inserting the base between the two sides of the spring, thereby causing the spring to be received 120 into the cut-away portion 11 of the base, and the latch stud received into the aperture 7' of the base, and thereafter, the base by means of the integral nibs 5, is secured to the frame member. By turning the pull piece 12 in 125 130

either direction, the latch stud 9, with its beveled latch head 13, will become either engaged or disengaged from the nosing 14 formed on the frame member 2, or as previously stated, from the aperture 8 formed in the base 6 of the fastener 4, as illustrated in Fig. 9 of the drawings, when it is desired to dispense with the nosing 14.

The fastener just described serves for additionally holding the frame members 1 and 2 in locked position, is carried by one of the catches or fasteners 3 and 4, and engages with the other of said catches or fasteners, and is independently operated from the catches or fasteners 3 and 4. The invention is not limited to the exact embodiment shown, but may be modified in various ways in the scope of the appended claims.

I claim:

1. In combination, two frame members movable relatively to each other, a spring-actuated auxiliary locking device rotatively secured to the top of one of said frame members and having locking engagement with the other of said frame members, comprising an apertured base recessed in its base and provided with a knob extending upwardly therefrom, a U-shaped apertured spring provided with recesses in one side thereof positioned in the recess of said base,

a latch stud passing through said apertured base and spring, said latch stud provided with a latch head having projections extending from one side thereof adapted to engage with the recesses in said spring for controlling the movement of said latch stud. 35

2. In combination, two frame members movable relatively to each other, a spring actuated auxiliary locking device rotatively secured to the top of one of said frame members and having locking engagement with the other of said frame members, comprising an apertured base recessed in its base and provided with a knob extending upwardly therefrom, a U-shaped apertured 45 spring positioned in the recess of said base, a latch stud passing through said apertured base and spring provided with a latch-head adapted to engage with the other frame member to have locking engagement therewith, 50 said spring and latch stud each provided with coöperating positioning means for controlling the movement of said latch stud.

This specification signed and witnessed this 9th day of July, 1917.

FRANZ A. FULLER.
